SAMPLE TAKING APPARATUS

Sosthene Robichaux, Saratoga, and George J.
Barrett, Houston, Tex.

Application April 15, 1932. Serial No. 605,464

7 Claims. (Cl. 255—72)

This invention relates to a sample taking apparatus.

An object of this invention is to provide apparatus for taking cores, or samples, of the formation being pierced in drilling wells and which embodies a drill stem and core forming drill and a barrel having a sample chamber to receive the cores, or samples, said barrel being located in said stem and a section thereof being mounted on anti-friction bearings to the end that said section of the barrel will not rotate with the stem and will not break up or injure the core or sample.

Another object is to provide an apparatus of the character described having fluid passageways whereby a flushing fluid may be supplied to the drill and embodying a novel construction whereby the flushing fluid may be excluded from the sample and sample chamber.

A further object is to provide a sample taking apparatus which is adapted to take either hard or soft cores or samples.

A further object is to provide a sample taking device having a sample receiving barrel that may be withdrawn from and reinserted in the stem without withdrawing the stem and drill from the bore.

With the above and other objects in view this invention has particular relation to certain novel features of construction, operation and arrangement of parts an example of which is given in this specification and illustrated in the accompanying drawing, wherein:

Figure 1 shows a vertical sectional view of the lower end of the apparatus.

Figure 2 shows a vertical sectional view of the upper end thereof.

Figure 3 shows an enlarged fragmentary vertical sectional view of the core barrel, and

Figure 4 shows a fragmentary vertical sectional view of the means for anchoring the core barrel.

In the drawing the numeral 1 designates the drill stem to the lower end of which a coupling 2 is attached and a core drill 3 is connected to this coupling by the drill collar 4. Leading downwardly through said collar and drill, from within the stem, are the channels 5 through which drilling fluid may be supplied from the stem to the drill to flush away the cuttings.

Fitted closely within the drill collar and attached to the drill there is a tubular housing 6 forming a guide which is spaced from the collar 2 and stem 1 and whose upper end is flared, as at 7.

The drill 3 has a central bore, or passageway 8, to admit the core, or sample, and this bore has an internal, upwardly facing seat 9 on which the

lower end of the lower section 10 of the core barrel may rest. Within the drill around the lower end of said barrel are any suitable anti-friction means said means, as shown, consisting of the raceway rings 11 and 12, with the anti-friction ball bearings 13 between said rings.

Within the core barrel, adjacent its lower end, there is a downwardly converging slip seat 14 whereon the slips 15 are mounted and said slips are held in place in any suitable manner, as by the inside, annular shoulder 16 beneath said seat and the coil pressure springs 17 which press against the upper ends of the slips.

The lower section 10 of core barrel is spaced from the housing 6 but the upper section 10' thereof, is fitted closely within the housing 6 to prevent the passage of the drilling fluid down between said section 10' and the housing 6 and thus excludes said drilling fluid from the sample receiving chamber of the core barrel. The sections 10, 10' are connected to swivel, said swivel connection referred to being formed by a flanged coupling 18 threaded onto one of said connected parts and in engagement with a head 19 of the other connected part and ball bearings 20 are interposed between the said connected parts whereby the lower section 10 of core barrel proper will remain stationary as the drill stem rotates in drilling. At the upper end of the section 10' of the barrel there is a valve cage 21 wherein the upwardly opening ball valve 22 is mounted.

Any suitable means may be provided for lowering the core barrel into place and for withdrawing it. As shown there is an anchor 23 attached to the cage 21 and pivotally mounted in said anchor, on the cross pin 24, are the oppositely working dogs 25, 25 whose lower ends work through oppositely arranged slots in said anchor and are adapted to engage underneath the inside annular shoulder 26 in the housing 6, and to be retained in such engaged relation by the pressure of a spring 27 between said dogs.

A dog actuator 28 works in the upper end of the anchor 23 and its lower end is bifurcated to embrace the upper ends of said dogs and a cross pin 29 is anchored to said actuator and works through the upwardly diverging slots 30, 30 in the upper ends of said dogs. The upper end of the actuator 28 has the head 31 thereon.

When the core barrel is located and secured in the drill stem, as shown in Figures 1 and 2, the core formed by the drill 3 will pass up into the sample chamber of the core barrel and the friction of the core with the lower section of the

barrel will cause said section to stand still and the core will not be broken up or injured by the rotation of the barrel section 10. As the barrel chamber is filled with the core or sample the 5 valve 22 will lift to permit air or water and the like in the sample chamber to pass out but said valve will prevent the entrance of drilling fluid into the sample chamber from above. As the core enters said chamber the slips 15 will move 10 upwardly and outwardly to permit the free entrance of said core.

When the core has been taken a suitable fishing tool may be lowered into the stem and engaged with the head 31 and the actuator pulled 15 upwardly and thereupon the pin 29 moving upwardly in the slots 30, 30 will move the upper ends of the dogs 26 inwardly causing a corresponding inward movement of the lower ends of said dogs whereby the dogs are disengaged 20 from the shoulder 26 and the core barrel released and it may then be withdrawn for an inspection of the sample. As the barrel is pulled upwardly the slips 15 will move downwardly and inwardly on the seat 14 and will grip and retain 25 the core.

In order to locate the core barrel in the stem 1 said barrel may be lowered and it will be guided into place by the guide 6 and when its lower end passes through the ring 12 and lands on 30 the shoulder 9, the dogs 25 will have passed beneath and will engage under the shoulder 26 and the barrel will be thus anchored in place. The fishing tool, whereby the barrel is lowered, may then be detached and removed and another core 35 taken and removed as before.

The drawing and description disclose what is now considered to be a preferred form of the invention by way of illustration only while the broad principle of the invention will be defined 40 by the appended claims.

What we claim is:

1. In a sample taking device a drill having an inlet for a core, a tube associated with the drill, a core receiver in said tube having a core receiving 45 chamber in communication with said inlet, anti-friction means for mounting said receiver whereby the tube may rotate independently of the receiver, said receiver being spaced from the tube and having an enlarged tubular portion 50 which fits closely within, and may rotate with, said tube.

2. In a sample taking device a core forming drill having an inlet for the core, a tube associated with the drill, a tubular receiver in said tube having a sample chamber arranged to receive the core entering through said inlet, said receiver having an enlarged section which fits closely in, and forms a water tight joint with, said tube, said receiver having an outwardly 55 opening valve adjacent its upper end and having core retaining means at its lower end.

3. In a sample taking device having a tube; a tubular sample receiver adapted to be inserted into said tube and having a sample receiving 65 chamber therein, said receiver having a reduced section spaced from the tube and an enlarged section which fits closely within, and forms a substantially fluid tight joint with the tube,

means connecting the sections to permit them to rotate relative to each other.

4. In a sample taking device having a tube and an associated core drill having a core inlet; a tubular sample receiver adapted to be inserted 80 into said tube and having a sample chamber in communication with said inlet, said receiver having an enlarged portion adapted to fit closely in the tube and a reduced portion adapted to be spaced from the tube and means connecting said portions to permit the enlarged portion to rotate with the tube independently of the reduced portion.

5. In a sample taking device having a tube and an associated core drill having a core inlet; a tubular sample receiver adapted to be inserted 85 into said tube and having a sample chamber in communication with said inlet, said receiver having an enlarged portion adapted to fit closely in the tube and a reduced portion adapted to be spaced from the tube and means connecting said portions to permit the enlarged portion to rotate with the tube independently of the reduced portion, and antifriction means whereon the reduced portion is mounted.

6. In combination, a drill stem, a drilling tool at the lower end of the stem having an inlet, a tubular housing anchored in the stem, a core barrel having a reduced lower section whose lower end is open and aligned with said inlet and 100 whose upper end is enlarged and fits closely within said housing, said sections of said barrel having a swivelling connection, an upwardly opening valve controlling the passageway through the barrel, an anchor in the housing 111 connected to the upper end of the core barrel, interlocking means carried by the anchor and housing respectively whereby said anchor and the barrel may be interlocked with the housing, a core retainer in the reduced section of the barrel, said anchor and barrel being insertable 115 downwardly into the housing and said interlocking means being releasable to permit the withdrawal of the anchor and barrel from the housing and drill stem.

7. A sample taking apparatus comprising a tubular drill stem, a drilling tool at the lower end of the stem having an inlet, a tubular housing anchored in the stem, a tubular core barrel 120 in the housing having a reduced lower section, whose lower end is open and aligned with said inlet and having an enlarged upper section which fits closely within said housing, said sections of said barrel having a swiveling connection, an upwardly opening valve controlling the 125 passage through the barrel, an anchor connected to the upper end of the core barrel, means carried by the anchor whereby said barrel may be locked within the housing, a core retainer carried by the barrel, said barrel being insertable 130 downwardly into the housing and said locking means being releasable to permit the withdrawal of the barrel from the housing and stem and a flexible line connected to the anchor by means of which said core barrel and anchor may be so 135 withdrawn.

SOSTHENE ROBICHAUX.
GEORGE J. BARRETT.
